UNITED STATES PATENT OFFICE.

JAMES T. RYAN, OF FRANKFORT, KENTUCKY.

WINDMILL LUBRICATING SYSTEM.

Application filed February 1, 1924. Serial No. 689,895.

To all whom it may concern:

Be it known that I, JAMES T. RYAN, a citizen of the United States, residing at Frankfort, in the county of Franklin and State 5 of Kentucky, have invented certain new and useful Improvements in Windmill Lubricating Systems, of which the following is a specification.

The invention relates to wind mills of the 10 type disclosed in my application for patent upon wind mill Serial Number 671,135, filed October 27, 1923, and has as an object the provision of a system of lubrication which will keep the moving parts continually 15 bathed in oil.

A further object of the invention is the provision of a lubricating system which will return surplus oil constantly to the oil reservoir.

20 A further object of the invention is the provision of a governing apparatus for a wind mill which will provide sufficiently high speed of rotating parts as to effectually spray the oil supplied by the lubricating 25 system and which will act efficiently as governing means, due to the speed of rotation of the governing element.

A further object of the invention is the provision of an oil-tight enclosure for the 30 governing apparatus which while retaining the oil within will exclude dust and dirt from the working parts.

Further objects of the invention will appear from the following description when 35 read in connection with the accompanying drawing showing an illustrative embodiment of the invention, and wherein—

Fig. 1 is an elevation;

Fig. 2 is a detail vertical section showing the lower portion of the shaft and connected parts, as well as the oil sump on an enlarged scale.

Fig. 3 is a detail vertical section of the upper portion of the mill showing the governing apparatus.

Fig. 4 is a detail horizontal section on line 4, 4 of Fig. 3.

Fig. 5 is a detail vertical section broken away to economize space and shown on an enlarged scale, illustrating some details of the preferred form of spider.

Fig. 6 is a detail horizontal section on line 6—6 of Fig. 5, and

Fig. 7 is a detail section of a form of ball-bearing for the upper bearing of the deflector and shield element.

As shown in Fig. 1, the mill comprises a supporting frame 10, a rotor 11, a shield 12 and deflector 13 connected at the upper portion to a conical rain shield 14, and at the lower portion to a spider 15, all as shown in my copending application above referred to.

Details of a desirable form of spider are shown in Fig. 5 in which a lower hub 80 is shown having a bearing 81 upon the frame 65 of the mill and arms 82 are shown riveted to projections 83 from the hub. An upper hub 84 and a lower hub 85 are shown carrying arms 86, 87, to which the blades 88 of the rotor are secured. To fix the hubs 70 84 and 85 rigidly to the shaft they are preferably provided with a tapering thread as at 89, 90 and jam nuts 91, 92 are provided to cause the hubs to pinch the shaft. If desired the threaded portion of the hubs may 75 be slotted (not shown) to allow contraction in a well known manner. A sleeve 93 is shown carried by the hub 85 and overlapping the hub to retain oil in the cavity 94 80 in the hub 80.

As disclosed in the said co-pending application the vane 16 is adapted to control the relation of the shield 12 and deflector 13 to the direction of the wind.

The governing apparatus, shown more 85 particularly in Fig. 3, is in principle the same as that shown in the co-pending application.

To provide a greater speed for the governor to increase its efficiency as a governor, 90 and also to more thoroughly spray oil, as will be described, the governor is geared up as follows: A gear 17 is rigidly secured to the hollow shaft 18. The circular plate 19, which serves as a centering device for 95 the conical rain shield 20 is journaled upon the shaft 18 for free rotation thereon, and has a bearing 21 preferably of the ball type upon the collar 22 to which the upper spider arms 23 of the rotor are secured. The plate 100 22 is rigidly secured to the shaft 18.

To secure the plate 19 to the rain shield 20 and to enclose the governing apparatus in a dust and oil-tight manner, there is shown a frusto-conical apron 24 bolted as 105 at 25 to the rain shield, and, as at 26, to the edge of the plate 19.

The ball governors 27 are shown as pivoted at their lower end at 28 to a collar 29, rigidly secured to a sleeve 30 journaled for 110 free rotation upon the shaft 18. Preferably a hardened washer 31 is secured to the

lower end of the collar 29 to take the wear of the relatively rotating parts at that point. Ball bearings may be interposed between the hardened washer 31 and the sleeve 30. Upon 5 the periphery of the collar 29 is a set of gear teeth in mesh with gears 32, which in turn are integral with other gears 33 in mesh with the teeth of gear 17. The gears are shown as journaled upon pins 34 having a bearing 10 at their lower ends in the plate 19; and at their upper ends in a yoke 35 the ends of which are downturned and secured to the plate 19, as at 36.

Due to the difference in size between the 15 gear 17 and the gear 33, and between gears 32 and the gearing upon the sleeve 29, the governor balls 27 will be revolved at a considerably higher speed than is the shaft 18.

The second connection of the governors 20 27, through the links 37, is to a sliding sleeve 38, as disclosed in my co-pending application, but in the present instance the conical member of the sleeve is provided with an upwardly opening recess 40 and has 25 a plurality of holes 41 in its periphery. As in the co-pending application referred to, downward movement of the cone 39 is adapted to act upon a crank 42, and through the shaft 43 cause movement of the vane 16.

To assist the springs 78 to return the 30 governor arms to normal when the cone 39 is excessively depressed and when the angle between the arms approaches 180° and also to cushion the movement of the cone 39 upon sudden increases of speed of the device, a helical spring 79 is placed around the sleeve 30. The spring 79 is preferably of such a length as to allow about two thirds of the movement of the cone to be unchecked.

To supply oil to the parts described, there 35 is shown an oil pump 44 actuated by means of a connecting rod 45, through a cam 46, preferably an eccentric, secured to the shaft 18, whereby a stroke of the pump is provided for each revolution of the shaft 18. The pump is shown as drawing from an oil reservoir 47 desirably housed in the base block 48 which supports the rotor of the 40 mill. When thus constructed oil will be drawn to the pump through pipe 49 and discharged through a pipe 50, leading to and discharging into the upper bearing 51 of the frame, as shown in Fig. 3. A plug 52 is shown in the shaft 18. To supply oil to the bearing of the shaft 18 within the journal 51, there is shown a channel or groove 53 in the surface of the shaft 18, terminating in an opening 54, delivering to a recess 55, thereby being adapted to lubricate the entire surface of the shaft 18, within the journal 51 and within the upper conical centering member 56 of the rain shield.

The peripheral recess 57 is also shown in 65 connection with the channel 53 and an

oil passage 58 is shown communicating therewith and adapted to convey oil to the bearing of the crank shaft 43.

A series of openings 59 are shown in the shaft 18 above the plug 52, through which 70 oil may escape and flow downward into the recess 40, a certain amount finding access through openings 60 to the bearing of the sleeve 30 upon the shaft 18.

The supply of oil through the pipe 50 is to be sufficient to feed oil to all of the main parts, and also to keep a sufficient quantity present in the recess 40, so that it may be thrown or sprayed by centrifugal force 75 through the cone openings 41 in the cone 38 80 to keep the whole of the mechanism of the governor bathed in oil.

The oil accumulating in the lower portion 85 of the apron 24 and upon the plate 19 will drain through holes 61 to a recess 62 in the bearing 22, thereby keeping the ball bearing 21 lubricated and from the recess 62 through oil passages 63 to the center of the hollow shaft, down which it flows, guided mainly by the inner surface of the shaft 18, finally gaining access through oil passages 64 and 65 to the reservoir 47, in the meantime thoroughly lubricating the ball bearing 66 upon which the lower end of the shaft 18 is 90 carried.

Some of the oil passing down the inner surface of the shaft 18 will find its way 95 through a passage 67 to the cupped top of the bearing 68 for the shield and deflector spider 15, and from there through a passage 69 to the bearing 70 for the wind shield and deflector elements carried by frame member 71. From this point there is shown a passage 72 to return the oil to the interior of the shaft 18. If desired a sheet metal shield 73 may be secured to the collar 74 provided 100 for the actuation of the governor rod 75, to cover the slots 76 to retain the oil in its downward passage. The rod 75 is adapted to act upon the pin 77 to depress the cone 38 to cause the vane to throw the shield 12 into the wind in the manner already described in my co-pending application above referred to.

In the form of bearing shown in Fig. 7, 115 the lower end of the casting 51' is shown as provided with an enlarged portion 95 within which is housed a radial ball-bearing 96 in which the upper end of the hollow shaft 18 is journaled. The apex of the rain shield element 56' is shown as enlarged to receive the enlarged portion 95. An annular oil recess 97 is preferably formed upon the interior of the portion 98 of the casting 56' and oil channels 99-100 are formed leading to the annular channel referred to. through the pipe 50, pieces of tubing 101 with their exposed ends cut on an angle are shown as projecting to the interior of the casting 51' from the channels 99—100.

5 Minor changes may be made in the physical embodiment of the invention without departing from its spirit.

I claim:

10 1. A wind mill and lubricating means therefor comprising, in combination, a lubricant reservoir, means actuated by said mill to draw from said reservoir and deliver lubricant to the top of the mill, means actuated by the mill to spray lubricant upon 15 mechanism of said mill and means to drain off and conserve surplus lubricant.

20 2. A wind mill and lubricating means therefor comprising, in combination, governing mechanism, means to deliver lubricant to said mechanism, and means actuated by said mechanism to spray the lubricant thereover.

25 3. A wind mill and lubricating means therefor comprising, in combination, governing mechanism, means to deliver lubricant to said mechanism, means actuated by said mechanism to spray the lubricant thereover, and means to collect and conserve surplus lubricant.

30 4. A wind mill and lubricating means therefor comprising, in combination, governing mechanism, means to drive said mechanism from the mill at an increased speed, means to deliver lubricant to said 35 mechanism, means actuated by the mechanism to spray lubricant thereover by centrifugal force and means to drain off and conserve surplus lubricant.

40 5. A wind mill and lubricating means therefor comprising, in combination, governing mechanism, an oil tight enclosure therefor, means to deliver lubricant to said mechanism, means actuated by the mechanism to spray lubricant thereover by centrifugal force, and means to collect surplus lubricant and deliver the same to other frictional surfaces of the mill.

45 6. A wind mill and lubricating means therefor comprising, in combination, a rotor, a wind shield and deflector mounted for rotation thereabout, a rain shield connected to said last named parts and journaled on the shaft of said rotor, governing mechanism housed in said rain shield, a 50 concave apron secured to said rain shield and surrounding said mechanism, means to deliver lubricant to said mechanism, means to spray the lubricant over the mechanism and means to conduct lubricant gathered 55 by said apron to other frictional surfaces of the mill.

60 7. A wind mill and lubricating means therefor comprising, in combination, a vertical hollow shaft, a rotor mounted on said

shaft to be driven by wind power, means 65 to deliver lubricant to the upper portion of said hollow shaft, means to supply lubricant therefrom to the bearings of the mill, means to return surplus lubricant from said bearings to the interior of the hollow shaft 70 and means below said shaft to receive and conserve the surplus lubricant flowing downward through said shaft.

8. A wind mill and lubricating means therefor comprising, in combination, a vertical shaft, a sleeve journaled on said shaft, multiplying gearing to drive said sleeve from said shaft at increased speed, centrifugal governing means driven by said sleeve, means actuated by said sleeve for 80 spraying oil over said governing mechanism, and means to conserve the surplus oil.

9. A wind mill and lubricating means therefor comprising, in combination, a vertical shaft, centrifugal governing means 85 actuated by said shaft comprising an inverted frusto conical cam sliding on said shaft, an annular recess in the base of said cam, means for delivering oil to said recess, and means to spray oil from said recess by 90 centrifugal force over the governing means.

10. A wind mill and lubricating means therefor comprising, in combination, a vertical hollow shaft, a rotor to drive said shaft by wind power, a reservoir adjacent the foot of the mill, means actuated by said shaft to draw oil from said reservoir and deliver the same to the top of said shaft, a closure adjacent the top of said shaft, governing means above said rotor actuated 100 by said shaft, an oil-tight housing for said governing means, said shaft having openings above said closure to deliver oil to the interior of said housing, means actuated by the governing means to spray the oil thereover, and means to conserve the surplus oil and return the same to said reservoir.

11. A wind mill and lubricating means therefor comprising, in combination, a vertical hollow shaft, a rotor to drive said shaft by wind power, a reservoir adjacent the foot of the mill, means actuated by said shaft to draw oil from said reservoir and deliver the same to the top of said shaft, a closure adjacent the top of said shaft, governing means above said rotor actuated by said shaft, an oil-tight housing for said governing means, said shaft having openings above said closure to deliver oil to the interior of said housing, means actuated by the governing means to spray the oil thereover, means to convey oil drained from said housing to the bearings of said rotor, an oil passage from said bearings to return the oil to the interior of the shaft, and means to return oil from the interior of the shaft to said reservoir.

JAMES T. RYAN.
